SPILL PORT CONTROL FOR FREE-PISTON UNITS

Andrew Kalitinsky, Eagleville, Conn., assignor to
United Aircraft Corporation, East Hartford,
Conn., a corporation of Delaware

Application August 23, 1944, Serial No. 550,886

3 Claims. (Cl. 230—56)

1

This invention relates to the control of spill ports in the compressor cylinders of a free-piston unit.

The copending application of Kalitinsky, Serial No. 550,884, filed August 23, 1944, describes a free-piston unit, the compressor cylinders of which have a number of rows of spill ports, each row of which is individually controlled for maintaining the desired length of piston stroke. A feature of this invention is an arrangement for automatically adjusting the rows of ports.

A stroke indicator for indicating changes in the position of the end of the piston stroke is disclosed in the copending Kalitinsky application, Serial No. 550,883, filed August 23, 1944, patented May 13, 1947, Pat. No. 2,420,483, in which a change in the position of the ends of successive strokes of the piston causes a change in pressure in a fluid. A feature of this invention is the automatic control of the spill ports from a stroke indicator or master control of this type.

Another feature is the actuation of the structure by which the spill ports are opened and closed in response to changes in an operating characteristic of the unit such as a change in the length of the piston stroke.

Other objects and advantages will be apparent from the specification and claims, and from the accompanying drawings which illustrate an embodiment of the invention.

Fig. 1 is a sectional view through the free-piston unit.

Fig. 2 is a sectional view of the restraining linkage.

Fig. 3 is a transverse section on line 3—3 of Fig. 1, with a part of the band actuating mechanism shown diagrammatically.

Fig. 4 is a diagrammatic view of the master control and the actuating mechanism for the spill ports.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 through one or more nozzles 32. Air compressed in the air spring cylinders on the power stroke returns the piston assemblies. The assemblies are always maintained at equal distances from the center of the engine cylinder by a linkage

2

which may include racks 34 and 36, Fig. 2, extending from the piston assemblies and meshing with a pinion 38 on a shaft 40.

Intake manifold 42 which extends around the compressor and engine cylinders, conducts air to intake valves 44 in the heads of the compressor cylinders through which air alternately enters opposite ends of the cylinders. The compressed air leaves the cylinders through discharge valves 46, also at opposite ends of the compressor cylinders and passes into a central scavenging chamber 48 and end chambers 50 and 52. These chambers may be interconnected by a scavenging manifold, not shown.

Compressed gas from the scavenging chambers enters engine ports 54 and 56 which are uncovered by pistons 12 and 14 at the end of the power stroke, thereby permitting air to be blown through the engine cylinder. Gas in the engine cylinder is discharged through exhaust ports 58 into exhaust manifold 60.

Each compressor cylinder has a number of axially spaced vents 62, each in the form of a row of spill ports in the cylinders to permit air to discharge from the cylinder without compression. Each vent, or row of ports, may be individually controlled by a band 64, Fig. 3, extending around the cylinder between projecting ribs 66 extending from the cylinder, said band having spaced openings 68 for alignment with the spill ports. This band may be held against the cylinder by a spring 70 and may be moved angularly, to open and close the ports, by a hydraulic motor 72 including a cylinder 74 and a piston 76 having its projecting rod 78 connected to a lug 80 on the band. The particular port closure shown is claimed in the copending application of Kalitinsky, Serial No. 550,884, filed August 23, 1944.

The intake manifold includes a housing 82 which may extend around the compressor cylinders, and end caps 82 and 84 on the housing forming passages to the intake valves at the outer ends of the compressors. The vents 62 open into the intake manifold.

When the air being pumped by the compressor has a high density, as at sea level atmosphere, all the rows of ports are open and only a small quantity of air is compressed. As the density decreases, as when the compressor operates at altitude, one or more of the rows of ports may be closed, beginning with the end rows, thus increasing the effective volume of the compressor. The several rows of ports permit adaptation of the compressor to substantially any altitude or to any density of air being pumped.

The rows of ports may be automatically opened and closed from the master control which produces a pressure change in a control fluid in response to changes in an operating characteristic of the unit, such as a change in the length of piston stroke. Referring to Fig. 4 the master control is actuated by a cam 86 turning with the pinion 38 as shown in Fig. 2. Since the pinion 38 is oscillated directly from the pistons the movement of cam 86 is proportional to the piston stroke.

Fluid under pressure from a constant pressure source enters a passage 88 in a casing 90 through a conduit 92. This passage intersects a bore 94 adjacent its outer end and a throttling screw 96 controls the rate of flow into bore 94. A branch passage 98 from passage 88 connects with a port 100 in bore 94. A plunger 102 in bore 94 has a groove 104 which connects a port 106 alternately with port 100 or with a port 108. Port 108 is connected by a passage 110 to the inner end of bore 94. Port 108 is connected by a channel 112 in casing 90 and in an adjoining casing 114 to the inner (left-hand) end of a bore 116 in casing 114. A piston 118 in bore 116 is moved to the right by a calibrated spring 120. A plunger 122 extends through the piston and carries on its projecting end a push rod 124. This rod carries a roller 126 held against cam 86 by a spring 128. Plunger 122 has a central passage 130 connecting with spaced grooves 132 and 134 in the plunger. Groove 132 aligns with openings 136 in a sleeve 138 carried by piston 118 and groove 134 is adapted to be uncovered by the end of sleeve 138 as the plunger is moved to the right by the cam as the pistons approach the outer ends of their strokes.

Fluid under pressure from the right-hand end of bore 94 enters the right-hand end of bore 116 through a connecting channel 140, moving piston 118 to the left against the spring 120. As plunger 122 is moved to the right by cam 86 the groove 134 is uncovered by sleeve 138 to permit discharge of fluid from the right-hand end of bore 116. The pressure in the right-hand end of bore 116 varies in accordance with the compression of the spring and as the piston stroke becomes shorter the piston 118 moves inward, increasing the spring tension and increasing the pressure at the end of bore 98.

Since the change in pressure on the right-hand end of plunger 102 is proportional to the change in the location of the end position of the piston stroke, the pressure on the inner (left-hand) end of plunger 102 which balances the pressure on the outer end must vary in the same manner. In this way the pressure in the discharge conduit 142 is proportional to the spacing of the actual end of the piston stroke from the extreme outer position of the piston, and changes in pressure in this conduit will be proportional to changes in the outer end position of the piston stroke. This pressure and change in pressure are used to move the control bands for the rows of spill ports.

The outer end of plunger 122 may reciprocate in a chamber 144 having an outlet conduit 146 connected to a sump, not shown. The inner end of bore 116 may be connected by a conduit 148 to the conduit 146. A bellows 150 connected by a conduit 152 to passage 140 may be used for minimizing surges in the controls.

Discharge conduit 142 may be connected to the end of a cylinder 154 in which is a piston 156. The piston is moved in one direction against the fluid pressure by a spring 158. The project-

ing piston rod 160 on the piston is connected to a valve plunger 162, Fig. 3, in a casing 164. This valve alternately directs fluid under pressure from an inlet port 166 to outlet ports 168 and 170 connected by ducts 172 and 174 to the opposite ends of the cylinder 174. When fluid is entering one one of cylinder 174 the other end of the cylinder is vented by valve plunger 162 through one of the vent ports 175 or 176. The piston rod 160

10 may be connected to a snap toggle including projecting arms 177 and 178 sliding in guides 180 and 182 with their outer ends connected by a spring 184. This arrangement assures movement of the valve to either of its end positions to cause the control band 64 to be moved from the position in which the ports are fully closed to a position in which the parts are fully open.

If the piston stroke shortens, for example, the master pressure increases until it will overcome the force of spring 158 and the spring 184 and move valve plunger 162 to cause the row of ports to be open. With the ports open the stroke lengthens and the master pressure decreases, thus lowering the pressure on piston 156. Spring 184, however, acting on the snap toggle prevents spring 158 from moving piston 156 until the piston stroke has lengthened beyond the increase in length caused directly by the opening of the row of ports. Without this pressure differential, the 20 reduction in master pressure resulting from opening the row of ports and thereby lengthening the stroke would immediately cause the ports to be automatically closed again.

Each row of ports is controlled by a similar band and each band is actuated by a separate mechanism. As shown in Fig. 4 a second cylinder 186, similar to cylinder 154, has a piston 188 held in the position shown by a spring 190, the strength of which is lower than the spring 158. This second device actuates an adjacent band and other devices may control the other rows. Since the outer master pressure varies in accordance with the changes in the piston stroke the rows of ports may be successively closed by adjusting the pressures of the springs 158 and 190 in the actuating devices for adjoining rows of ports so that the successive rows will be opened at different control pressures. As a result, the rows or ports may be closed successively in any predetermined order.

50 As the piston stroke shortens, the master control pressure increases to a pressure sufficient to shift the piston 188 which controls one of the inner rows of ports and causes this row of ports to be opened, thereby reducing the effective volume of the compressor. If the stroke continues to shorten, the control pressure increases enough to overcome the tension of the spring controlling the piston 156 for an adjacent row of ports, thereby causing a second row to be opened for further reducing the effective volume of the compressor and tending to increase the length of the piston stroke.

60 If the stroke lengthens, the reverse takes place and the rows of ports are successively closed. In the arrangement shown, the compressor being double-acting, the master control shown may control the outer three rows of ports, and a similar master control, not shown, which is responsive to changes in the position of the inner end of the piston stroke, may adjust the inner three rows of ports.

70 It is to be understood that the invention is not limited to the specific embodiment herein illustrated and described, but may be used in other

ways without departure from its spirit as defined by the following claims.

I claim:

1. In a free-piston unit, engine and compressor cylinders, a piston assembly moving in said cylinders, said compressor cylinder having a number of axially spaced circumferentially extending rows of spill ports, a band movable into a position for closing each row of ports and means for moving each band separately, in combination with 10 means responsive to changes in the end position of the piston stroke for causing operation of each band moving means for closing the rows of ports individually.

2. In a free-piston unit, engine and compressor cylinders, a piston assembly reciprocating in said cylinders, said compressor cylinder having a plurality of circumferential rows of ports, and closure means for opening and closing the ports of each row separately, in combination with a master control adapted to vary the pressure of a fluid in response to changes in the piston stroke, and means responsive to the change in fluid pressure for procuring operation of each of said port closure means separately, the master pressure for closing the ports being different from the master pressure at which the ports are opened.

3. In a free-piston unit, engine and compressor cylinders, a piston assembly reciprocating in said cylinders, said compressor cylinder having at least one row of ports, and a band movable for closing or opening said ports, in combination

with a master control for varying the pressure in a control fluid in response to changes in the length of the piston stroke, means actuated by said fluid for causing the band to be moved to open or close the ports, and means maintaining a pressure differential between the port opening and port closing pressures of the fluid.

ANDREW KALITINSKY.
